mesne assignments, to S. Sternau & Co., Inc.,
New York, N. Y., a corporation of New York

Application December 28, 1933, Serial No. 50,244

Term of patent 14 years

To all whom it may concern:

Be it known that I, LOUIS H. MORIN, a citizen and,
of the United States and residing at New York,
in the county of New York and State of New York,
have invented a new, original, and ornamental Design for an Inhaler, of which the following is a specification, reference being had to the accompanying drawing, forming part thereof.

Fig. 1 is a side view of the complete inhaler;

Fig. 2 is a side view of the inhaler with the casing or cover removed, and showing my new design.

I claim:—

The ornamental design for an inhaler, as shown and described.

LOUIS H. MORIN.
